DISPLAY TRAY

Richard L. Emery, Fairfield, Maine, assignor to Keyes Fibre Company, Portland, Maine, a corporation of Maine

Filed Sept. 18, 1959, Ser. No. 57,601

Term of patent 14 years

(Cl. D58—13)

FIG. 1 is a top plan view of a display tray showing my new design;

FIG. 2 is a side elevation thereof, the opposite side being the same in appearance;

FIG. 3 is a cross-sectional view on the line 3—3 of FIG. 1; and

FIG. 4 is an enlarged fragmentary cross-section on the line 4—4 of FIG. 1.

The dominant features of my design reside in the portions shown in full lines.

I claim:

The ornamental design for a display tray, as shown and described.
